United States Patent Office

Des. 225,113
Patented Nov. 14, 1972

225,113

VIDEO TELEPHONE UNIT

Donald Michael Genaro, Haworth, N.J., John Niel McGarvey, Drexel Hill, Pa., and Frederick Allen Rosebrock, Greenfield, Ind., assignors to Bell Telephone Laboratories, Incorporated, Murray Hill, N.J.

Filed July 16, 1971, Ser. No. 163,555

Term of patent 14 years

Int. Cl. D14—03

U.S. Cl. D26—14

FIG. 1

Des 225,113

PAGE 2

FIG. 2

Des 225,113

PAGE 3

FIG. 3

FIG. 1 is a lower left front perspective view of a video telephone unit showing our design;

FIG. 2 is a front perspective view;

FIG. 3 is a front perspective view showing a modified embodiment in which the unit is asymmetrical about the front center line; and

FIG. 4 is an upper left front perspective showing the asymmetrical design.

The rear of the unit is plain and unornamented. The broken line representations of the human form illustrated in FIGS. 1 and 4 are shown for illustrative purposes only.

We claim:

The ornamental design for a video telephone unit, substantially as shown and described.
